DESIGN FOR A GAME BOARD

Ralph W. Byrer, Rockford, Ill.

Application August 11, 1945, Serial No. 121,382

Term of patent 3½ years

(Cl. D34—5)

To all whom it may concern:

Be it known that I, Ralph W. Byrer, a citizen of the United States, residing at Rockford, in the county of Winnebago and State of Illinois, have invented a new, original, and ornamental Design for a Game Board, of which the following is a specification, reference being had to the accompanying drawing, forming part thereof.

In the drawing:

Fig. 2 is a section taken along the line 2—2 of Fig. 1.

The design is especially characterized by the representation on the background of military bombing targets.

I claim:

The ornamental design for a game board, substantially as shown and described.

RALPH W. BYRER.
